(57) **CLAIM**

The ornamental design for a game feeder support, as shown and described.

DESCRIPTION

FIG. 1 is a pictorial view of a game feeder support according to the present invention;

FIG. 2 is an opposing view of the game feeder support shown in FIG. 1;

FIG. 3 is a left side view thereof;

FIG. 4 is a right side view thereof;

FIG. 5 is a back view thereof;

FIG. 6 is a bottom view thereof; and,

FIG. 7 is a top view thereof.

The broken lines shown in the figures are for illustrative purposes only and form no part of the claimed design.
